UNITED STATES PATENT OFFICE.

HARRY FOTHERGILL, OF WESTMINSTER, LONDON, ENGLAND.

EVAPORATOR.

Application filed August 2, 1924, Serial No. 729,788, and in Great Britain August 24, 1923.

This invention relates to evaporators of the kind in which the liquid to be evaporated is first heated and afterwards introduced into a chamber of lower pressure in which a portion of the liquid flashes into vapour, the liquid being maintained in continuous circulation through the heater and flashing chamber by means of a pump, as for example in the manner described in the specification of my prior application No. 607,108.

The object of the present invention is to provide improvements in evaporators of the kind referred to.

In accordance with the principal feature of the present invention the flash or evaporating chamber is arranged around the heater so that the apparatus is in the form of a self-contained unit. From the lower part of the evaporating chamber the liquid which is not evaporated is withdrawn by a pump and delivered through the heater again in continuous circulation, additional make-up liquid being admitted into the system as and when required, and for the purpose of preventing the liquid increasing in density a portion of the liquid in continuous circulation may be discharged from the apparatus on the delivery side of the pump, thus avoiding undue concentration of the liquid.

When operating with liquids containing scale-forming matter, the heating surfaces in the heater are liable to become covered by a deposit, and under such conditions would require cleaning periodically. For this purpose in accordance with the present invention the heating elements may be so arranged that they can be quickly removed from the apparatus, and if desired a spare set of elements introduced into the evaporator so that the process of evaporation may be continued without stoppage of the plant except during the short time when the heating element is being changed.

With the object of obtaining a high speed of liquid through the tubes of the heater and thereby preventing the formation of scale in the tubes, the heater may be divided into a number of passes so that the liquid passes through groups of tubes in series, the last group discharging into the pipe or passage leading to the evaporating chamber. The heater liquid is preferably introduced into the evaporating chamber through

nozzles which may in accordance with the invention maintain a head on the discharge side of the heater and thus prevent any flashing or boiling of the liquid before it enters the evaporating chamber. The liquid system may be so designed that the head produced will require a pressure at the pump discharge in excess of atmospheric pressure although the pressure in the evaporating chamber may be below atmosphere, thus permitting of the continuous discharge of concentrated liquid without the use of a special extracting device. These nozzles also have the advantage of producing bursting jets of liquid which materially assist in breaking up the liquid and promoting efficient evaporation without priming.

The steam required for heating purposes may be supplied from any convenient source and the apparatus may work under any desired pressure depending on the conditions and requirements of the plant. For example, steam for the heater may be bled from a low pressure section of a steam turbine and the evaporator chamber maintained under vacuum by connection to the main condenser of some other condenser or distiller under vacuum.

High pressure steam may be led direct into the heater for raising the temperature of the liquid, but with the object of avoiding a high temperature in the heater and the baking of scale on the tubes, I prefer to use such high pressure steam in one or more ejector nozzles designed to extract vapour produced in the evaporator and compress such vapour into the heater. Two or more of these ejector nozzles or compressors may be arranged in series, and by using a portion of the vapour from the evaporator in this manner the quantity of high pressure steam required is reduced and the efficiency of the plant is thereby considerably increased.

The accompanying drawings, Figs. 1, 3, 4 and 5, show in sectional elevation convenient forms of apparatus constructed in accordance with the present invention, the same letters of reference being used to denote similar parts in the various drawings. Fig. 2 is a sectional plan view on the line A—A in Fig. 1, and Fig. 6 is a cross section on the line B—B in Fig. 5.

In each example the heater consists of a number of straight tubes *a* arranged within

the casing *b* having an inlet pipe *c* for the supply of heating steam, and an outlet pipe *d* for the discharge of the drainage water. Arranged around the casing *b* of the heater 5 is an outer vessel *e* which forms the evaporating chamber which is essentially at a lower pressure than that corresponding to the temperature of the liquid discharged into it from the heater, and from this chamber 10 the liquid to be evaporated is withdrawn through the pipe *f* by the pump *g* and discharged through the tubes *a* of the heater back again into the evaporating chamber through the nozzles *h*. The steam liberated 15 from the liquid on leaving the nozzles passes away from the evaporator through the pipe *p* which may be connected to a condenser. In Figs. 1 and 2 the heater is vertically disposed, the evaporating chamber being 20 concentrically arranged around the upper portion of the heater, the arrangement being such that the heated liquid on leaving the top of the heater is introduced into the top of the evaporating chamber through the 25 nozzles *h*. Additional make-up liquid is admitted through the pipe *m* into the vessel *e* forming the evaporating chamber by means of an automatic float control *l* which maintains the liquid level therein, and a portion 30 of the liquid in continuous circulation is discharged through the pipe *n* for the purpose hereinbefore described.

In Fig. 3, which is a modification of Fig. 1, high pressure steam is utilized for raising the temperature of the liquid passing through the heater, and with the object of avoiding a high temperature of steam in the heater, the high pressure steam supply *o* is connected to the nozzle *s* of the ejector *t* 35 which is designed to withdraw from the pipe *p* a portion of the vapour produced in the evaporator and compress such vapour into the heater through the pipe *e* in a known manner. Additional steam, such as 40 exhaust steam from auxiliary machinery, may be admitted through the pipe *r*. The liquid headers *x* and *y* of the heater, are divided into compartments so arranged that the liquid passes through groups of tubes in 45 series.

In Fig. 4 the lower liquid header *y* is connected to the heating tubes only by which it is suspended in the steam space of the casing *b*, the upper header *x* being provided with the necessary inlet and outlet 55 passages and secured, as by bolts, to the body of the evaporator. With such an arrangement it will be readily understood that by disconnecting the upper header from the body of the evaporator the water headers and heating elements may be quickly removed and a clean set of heating elements together with their water headers introduced into the evaporator. The heated water is 60 delivered from the heater through the pipe 65

v into an annular passage *w* surrounding the vessel *e*, and from this passage the water is introduced into the evaporating chamber through a ring of circumferentially disposed nozzles *h* which are preferably arranged to spray the water in a peripheral film over the inside surface of the vessel *e*. A baffle *u* is provided to prevent water being sprayed into the steam space in the upper part of the vessel *e* and further baffles *j* and *k* are arranged in the lower part of the heater to collect the deposits which can be periodically removed by taking off the cover *z*.

Figs. 5 and 6 show an evaporator in accordance with my invention in which the heater is placed horizontally, the arrangement of the headers and tubes being similar to that shown in Fig. 4 so that they may be withdrawn from one end of the casing *b* for cleaning purposes when required. The heated water from the header *x* is delivered through the pipe *v* to the passage *w* from which it is sprayed into the evaporating chamber through the nozzles *h*, a baffle *u* being placed over the nozzles *h* as shown. A vapour separator *q* may be provided when required.

The evaporating chamber, whatever the particular form of the apparatus, is always maintained at a lower pressure than that corresponding to the temperature of the liquid discharged into it from the heater, but this does not necessarily mean that it is under vacuum. If the pressure and corresponding temperature in the heater are high enough the evaporating chamber may be maintained at atmospheric or even higher pressure.

What I claim and desire to secure by Letters Patent is:—

1. Apparatus for evaporating liquids, comprising a vessel in which the liquid to be evaporated is heated, an evaporating chamber through which said heater passes, and a pump for circulating liquid from the lower part of said evaporating chamber and through said heater and again into said evaporating chamber.

2. Apparatus for evaporating liquids comprising a vessel in which the liquid to be evaporated is heated, an evaporating chamber, said heater passing through said evaporating chamber, and a pump for circulating liquid through said heater and into said evaporating chamber.

3. Apparatus for evaporating liquids comprising a vessel constituted by tubular surfaces connected to headers in which the liquid to be evaporated is heated, an evaporating chamber, said heater passing through said evaporating chamber, and a pump for circulating liquid from the evaporating chamber through said tubular surface heater and back into said evaporating chamber.

4. Apparatus for evaporating liquids comprising a vessel in which the liquid to be evaporated is heated, an evaporating chamber, the heater passing through said evaporating chamber, spraying nozzles adapted to spray heated liquid from the heating vessel into the evaporating chamber, and a pump for circulating liquid from the bottom of the evaporating chamber through said heater and thence to said spraying nozzles and into said evaporating chamber.

5. Apparatus for evaporating liquids comprising a vessel in which the liquid to be evaporated is heated, an evaporating chamber, said heater passing through said evaporating chamber, circumferentially disposed spraying nozzles adapted to spray sideways so as to project a peripheral film into the evaporating chamber, and a pump for circulating liquid through said heater and thence to said spraying nozzles and into said evaporating chamber.

6. Apparatus for evaporating liquids comprising a heater consisting of tubes arranged between headers, an evaporating chamber through which said tubes pass discharge nozzles leading from the heater to the evaporating chamber, and a pump for circulating the collected liquid from the evaporating chamber through the heater and thence through the nozzles again into the evaporating chamber.

7. Apparatus for evaporating liquids comprising an evaporating chamber having an internal circular chamber, a heater located in said circular chamber so as to pass through said evaporating chamber, means for maintaining in the evaporating chamber a pressure lower than that corresponding to the temperature of the liquid in the heater, and a pump for circulating the liquid from the evaporating chamber through the heater and discharging it again into the evaporating chamber.

8. Apparatus for evaporating liquids comprising a vessel in which the liquid to be evaporated is heated, an evaporating chamber, said heater passing through said evaporating chamber and a pump having its suction side connected to the lower end of the evaporating chamber and its delivery side adapted to deliver both to the heater and the evaporating chamber.

9. Apparatus for evaporating liquids comprising a vessel constituted by tubular surfaces connected to headers in which the liquid to be evaporated is heated, an evaporating chamber through which said heater passes, a pump for circulating liquid through said tubular surface heater and evaporating chamber, a connection from the suction side of the pump to the lower part of the evaporating chamber beneath the level of the liquid collected therein and a

connection from the delivery side of the pump to a header and to nozzles projecting into the evaporating chamber.

10. Apparatus for evaporating liquids comprising an evaporating chamber having an internal circular chamber, a heater located in said circular chamber so as to pass through said evaporating chamber and adapted to be removed in one piece from said circular chamber, means for maintaining in the evaporating chamber a pressure lower than that corresponding to the temperature of the liquid in the heater, and a pump for circulating the liquid through the heater, and discharging it into the evaporating chamber.

11. Apparatus for evaporating liquids comprising a vessel in which the liquid to be evaporated is heated, an evaporating chamber, spraying nozzles adapted to spray heated liquid from the heating vessel into the evaporating chamber, a baffle for preventing the spray from said nozzle entering the steam space of the evaporating chamber, and a pump for circulating liquid through said heater and thence to said spraying nozzles and into said evaporating chamber.

12. Apparatus for evaporating liquids comprising a cylindrical vessel having its axis vertically disposed, a liquid header arranged at each end of said vessel and connected together by vertical tubes through which the liquid to be heated is circulated by means of a pump, and an evaporating chamber through which the heating vessel passes and into which the heated liquid is delivered.

13. Apparatus for evaporating liquids comprising a vessel in which the liquid to be evaporated is heated, an evaporating chamber through which the heater passes, spraying nozzles adapted to spray heated liquid from the heating vessel into the evaporating chamber, baffles in the lower part of the evaporating chamber serving to collect deposits from the liquid, and a pump for circulating liquid through said heater and thence to said spraying nozzles and into said evaporating chamber.

14. Apparatus for evaporating liquids comprising a vessel in which the liquid to be evaporated is heated, an evaporating chamber through which the heater passes, spraying nozzles adapted to spray heated liquid from the heating vessel into the evaporating chamber, a baffle for preventing the spray from said nozzles entering the steam space of the evaporating chamber, baffles in the lower part of the evaporating chamber serving to collect the deposits from the liquid, and a pump for circulating liquid through said heater and thence to said spraying nozzles and into said evaporating chamber.

15. Apparatus for evaporating liquids comprising an evaporating chamber into which heated liquid is introduced, a heater vessel in which the liquid is heated said heater vessel passing through said evaporating chamber, a circulating pump having its suction pipe connected to the lower end of the evaporating chamber beneath the level of the liquid collected therein, the liquid discharged by said pump passing through said heating vessel and thence into the evaporating chamber above the level of the liquid collected therein.
16. Apparatus for evaporating liquids comprising a vessel in which the liquid to be evaporated is heated, an evaporating chamber through which said heater passes, a pump for circulating the liquid through said heater, and discharging it into the evaporating chamber, an outlet on the discharge side of the pump between said pump and said heater and means for producing a head upon the pump such as will require a pressure on the pump discharge in excess of atmospheric pressure whereby the continuous discharge of concentrated liquid is permitted without the use of any special extraction device.
17. Apparatus for evaporating liquids comprising a vessel in which the liquid to be evaporated is heated, an evaporating
- chamber, said heater passing through said evaporating chamber, spraying nozzles adapted to spray heated liquid delivered to them by a circulating pump into the evaporating chamber and to offer such resistance to the flow of the heated liquid that the pressure on the discharge side of the circulating pump is in excess of atmospheric pressure and a pipe connection on the delivery side of the pump for the discharge of concentrated liquid against atmospheric pressure.
18. Apparatus for evaporating liquids comprising a heater, an evaporating chamber to which the heated liquid is delivered, a pump for circulating the liquid through the heater and to the evaporating chamber, nozzles to which the heated liquid is delivered by the circulating pump said nozzles being so designed as to offer such resistance to the flow of liquid through them that the pressure in the discharge side of the circulating pump is maintained above atmospheric pressure and a discharge pipe connection for concentrated liquid leading from the discharge side of pump through which concentrated liquid is delivered against atmospheric pressure.

In testimony whereof, I affix my signature.

HARRY FOTHERGILL.
